United States Patent Office.

WILLIAM ATKINSON, OF PHILADELPHIA, PENNSYLVANIA.

Design No. 3,441, dated April 6, 1869.

DESIGN FOR A GUIDE AND FRICTION-BRAKE FOR SHUTTLE-LOOMS.

The Schedule referred to in these Letters Patent and making part of the same.

To all whom it may concern:

Be it known that I, WILLIAM ATKINSON, of Philadelphia, county of Philadelphia, and State of Pennsylvania, have originated and invented a new Design for a "Combined Pusher-Guide and Friction-Brake for the Box-Motion of Two-Shuttle Looms," of which the following is a full, clear, and exact description, reference being had to the accompanying drawings, making part of this specification.

Figure 1 is a front view, and

Figure 2, a back view of the "combined guide and brake."

a is a rectangular plate, with narrow projections, *a'*, *a''*, extending horizontally the entire length of the plate.

From this proceeds the main rib *b*, bent downward, to form the base of the rectangular opening, *c d e f*, when it turns downward at right angles, supporting at its extremity the arch *K*.

The parallel sides of this opening, *c d e f*, are formed by the vertical cheeks *c d* and *e f*, with ribs *g* and *h*. *g* extends to the plate *a* and connects it with the cheek *c d*.

h takes a turn at right angles at *i*, to support, in connection with *b*, the arch *K*.

This arch has side pieces *l l*, whose exterior is concentric with *K*, and whose sides are parallel with the plate *a*, and rectangle *c d e f*, as shown by red lines *q q q q* in fig. 2.

The fillet *m* is in the same plane as *g*.

The object may be made "right and left," the one shown on the drawing being "right hand."

I claim, as my invention, the design for a pusher-guide and friction-brake for a loom, as herein set forth and shown.

Witnesses:

WILLIAM ATKINSON.
C. C. KLEIN,
CHAS. E. PANCOAST.
